FREE PISTON MOTOR COMPRESSOR

Hermann Jänicke, Dessau, Germany, assignor to
 Therese Junkers, Gauting, near Munich, Germany

Application February 23, 1935, Serial No. 7,787
 In Germany March 9, 1934

20 Claims. (Cl. 230—56)

My invention relates to free piston motor compressors. It is an object of my invention to provide means whereby the output of compressors of the kind aforesaid can be controlled in a particularly simple and efficient manner.

In my copending U. S. application Serial No. 710,483 I have disclosed a method of controlling a free piston motor compressor by varying the length of stroke and the pressures thereof, e. g. 10 the suction or discharge pressure, or a combination of both these pressures. My copending U. S. application Serial No. 7,786 discloses the control of a free piston motor compressor by means of a variation of the dead space and the fuel supply 15 in a manner such that the piston stroke always remains approximately constant, independently from the variation of the compressor output, while my copending U. S. application Serial No. 7,788 discloses the regulation of a free piston motor compressor by the simultaneous variation 20 of at least two of the variables, which at a predetermined constant stroke of the piston determine the output of the compressor as well as the return energy in such a manner that the portion 25 of the total return energy available for the compression of the motor charge must always remain approximately constant.

In free piston motor compressors comprising a combustion chamber and one or more compressor chambers, and one or a plurality of freely reciprocating pistons, it has already been suggested to vary the performance of the compressor by varying the length of stroke of the free pistons. Such variation of stroke involves certain drawbacks, as thereby the control of the motor part of the machine, which is derived from the movement of the free pistons, is subjected to undesirable variations.

It is an object of my invention to enable the 40 performance of the compressor to be varied within wide limits at substantially constant stroke.

This is effected according to the present invention by regulating the performance of the compressor by varying the pressures and, at the 45 same time, influencing the supply of fuel to the combustion chamber of the motor in such manner that the stroke of the free pistons remains substantially constant.

In order to accomplish this, I may vary 50 (a) The delivery pressure; the performance drops when the pressure is increased, and vice versa;

(b) The suction pressure; the performance drops if this pressure is lowered, and vice versa;

(c) The delivery and suction pressures may be

varied at the same time; they may be varied in opposite senses, in which case the influences exerted on the performance by such variations of pressure add. Alternatively they may be varied in the same sense, in which case the performance varies in conformity with the difference between the influences of the pressure variations. In the case last mentioned the proportion of the two pressures may be constant and, if the initial temperature is constant, the final temperature of the 10 compressed gas will also remain constant.

In some cases the problem is to vary the amount of energy taken up or of energy delivered, by additional chambers such as, for instance, pneumatic buffers which store compression energy 15 during one stroke and deliver it during the subsequent stroke, this delivered energy, together with the energy which is released in the compressor proper upon the return stroke, compressing the charge in the combustion chamber. In such additional chambers the same procedure 20 may be adopted as in the compressor chambers proper, i. e. a variation of pressures, such as, for instance, the initial pressure of compression, at substantially constant stroke of the free piston or pistons.

The controls to be effected according to this invention, i. e., the variation of pressures and the variation of the quantity of fuel supplied to the motor per power stroke, may be effected 30 either manually or automatically, or one of them manually, the other automatically.

Manual control is adopted, for instance, if there arise comparatively few or slow variations of the demand for compressed gas, or if the requirements as to the exactitude of control are not high. With such a control the variations of pressure as well as the variation of the fuel supply 35 may be derived from the same control member (a hand wheel, a lever, or the like) so that each 40 control operation requires only the actuation of this one member.

If both controls are effected automatically, they may be influenced by the variations of a single source of power, for instance, by the pressure 45 in a storage tank arranged in series with the compressor. In that case both control operations are connected in parallel and are suitably tuned with respect to each other.

However, it is also possible, to render one control operation dependent of the other, for instance by again regulating the pressure in the compressor in dependency upon the pressure in a storage tank, while the supply of fuel is regulated in dependency upon the pressure in the 55

compressor. In this case the two control operations are connected in series.

It is further possible to render the two control operations dependent from distinct conditions which are not directly related to one another, for instance, to again vary the pressure in the compressor in dependency upon the pressure in the storage tank, but to regulate the supply of fuel to the motor part in dependency upon the 10 stroke in such manner that this stroke remains substantially constant.

I will now proceed to describe my invention with reference to the drawings affixed to this specification and forming part thereof, in which 15 several embodiments of this invention are illustrated diagrammatically by way of example.

In the drawings

Figs. 1, 2, 6 and 8 are axial sections of free 20 piston motor compressors with oppositely reciprocable pistons, each of the last two figures showing one-half of the machine while

Figs. 3, 4 and 5 are diagrams showing pressures plotted against stroke for the compressors illustrated in Figs. 1 and 2, and

25 Fig. 7 is a similar diagram for the pneumatic buffer illustrated in Fig. 6.

In the free piston motor compressors shown in Figs. 1, 2, 6 and 8, 1 is the casing of the motor and 2 is the central combustion chamber with a 30 compressor chamber 3 at each end. The free pistons are formed by engine pistons 4 and compressor pistons 5 which are directly connected. In order to warrant absolute synchronism of the 35 opposite reciprocatory movements of the pistons, they are connected by suitable mechanism, for instance a rack 15 connected to each piston, the racks meshing at diametrically opposite points with a pinion 16 which is mounted for rotation in a fixed position on the casing 1. The left 40 hand motor piston controls the scavenging ports 6 and the right hand motor piston controls the exhaust ports 7 in the wall of the motor cylinder. The residual compressed gas which remains over in the dead spaces of the compressor at the end 45 of every power stroke expands and forces the free pistons toward each other. When the pressure in the compressor cylinders has dropped to suction pressure, fresh gas is drawn in through the suction valves 8 and, at the same time, the 50 charge in the combustion chamber 2 is compressed. Toward the end of the return stroke liquid fuel is injected into the combustion chamber 2 through pipe 22 and injection nozzle 23 by means of a fuel pump having a piston 20 and 55 a cylinder 21, and the mixture is ignited. The fuel pump, which is more fully described in my copending application Serial No. 710,483, is operated by a cam 24 formed on the rack 15, which, when the piston is near the end of its inward 60 stroke, turns a rocker 25 which displaces the pump piston 20 against a spring 26. The products of combustion in the combustion chamber force the pistons apart, the gas which has been drawn into the compressor cylinders, is compressed and conducted to a storage tank 13 through delivery valves 9, delivery pipes 10 and delivery main 11. A pipe 14 distributes the compressed gas to the individual stations where it is required. A spring-loaded check valve 12 is provided in the main 11 for holding the compression pressure in the compressor chambers at a predetermined minimum even if the pressure in the reservoir should be lower than the minimum, for instance in consequence of heavy tappings 75 of compressed gas, or when the compressor is

started. The check valve 12 may consist simply—e. g. in a manner similar to that shown in Fig. 1—of a valve body 41, 42, which a spring 40 tends to close. The top of this spring abuts against a spring abutment 44, which, however, 5 in contradistinction to the showing of Fig. 1, can not be varied as to its position, but may be provided either as the cover of the valve casing itself or as some other part rigidly connected with said casing. In this case the force of the 10 spring acting upon the valve body is always maintained constant. Since the delivery pressure in the compressor is solely determined by the force of the spring, the delivery pressure in the compressor likewise can always be maintained 15 at a predetermined minimum value, i. e. may be constant, as indicated in Fig. 4 of the application, according to which the suction pressure only is varied, while the delivery pressure, despite the aforesaid variation, has remained constant. On the other hand the check-valve 12 can be arranged for a variable force of the spring 40 in such a manner that the delivery pressure of the compressor also is rendered variable. A 20 valve of this kind is described below in greater 25 detail with reference to Fig. 1.

The amount of fuel supplied to the motor per power stroke is regulated automatically in dependency upon the pressure in the storage tank 13 by turning the pump piston. To this end a 30 spur gear 30 is rigidly connected to the pump piston 20. A rack 31 meshing with the spur gear is supported by a piston 32 mounted to slide in cylinder 33. A compression spring 34 acts on one face of the piston, while the pressure in the tank 13 acts on the other face. The position of the piston 32 is thus determined by the pressure of the tank 13, and consequently the amount of fuel delivered at each stroke of the pump is a 35 function of this pressure.

Figs. 1 and 2 further illustrate means for regulating the compressor performance by a variation of pressures.

As shown in Fig. 1, a valve loaded by a spring 40 and opening toward the storage tank is inserted in the main 11 leading to the storage tank. The spindle 41 of the valve has the size of a piston so that the valve seat 42 is relieved of the pressure in the tank, and the delivery pressure of the compressor is determined by the tension of spring 40 exclusively. This spring tension, in the example illustrated, is regulated automatically in dependency upon the pressure in the tank. To this end a wedge member 45 is inserted between the end wall 43 of the valve casting and the spring plate 44 acting like a piston. The wedge member is connected to a piston 49 which is loaded, on one side, by the tension of a pressure spring 47, while its other side is connected to the tank 13 through a pipe 48, so that the piston 49 is acted upon by the pressure in this tank. When the pressure in the tank 13 increases beyond the normal, the piston 49 and wedge 45 move to the left, the tension of the 55 valve spring 40 is increased, the delivery pressure of the compressor rises in proportion and the performance is reduced. Obviously the increase of pressure in the compressor can be much greater than the increase of pressure in the tank 13, and the regulation will therefore be rapid and powerful.

If it is desired to manually regulate the compression pressure, the wedge 45 and the means for shifting it are replaced by a threaded spindle 75

which is inserted in the end wall 43 of the valve casing and exerts pressure on the spring plate 44.

Fig. 2 shows means for regulating the performance of the compressor by varying the suction pressure. Here all the suction valves 8 are connected to a suction pipe 51 in which a throttle valve 50 is mounted to slide, which is connected to a piston 53 which, through a pipe 54, is acted upon by the pressure in the tank 13 in such manner that this pressure tends to close the throttle valve, while a spring 55 counteracts the pressure on the piston. The spring is so designed that the throttle valve is closed in proportion as the pressure in the tank 13 rises beyond the normal, and the suction pressure is progressively reduced.

The control of the supply of fuel to the motor may be effected in dependency upon the pressure in the tank, as shown in Fig. 1.

The fuel supply may, however, also be regulated in dependency upon the suction pressure, as shown by way of example in Fig. 2. To this end the pipe 35 leading to the cylinder 33 of the fuel-regulating device, instead of being connected to the tank 13, is connected to the compressor chamber 3, this connection ending at 59 in the vicinity of the end face of the compressor piston 5 when this piston has just started for the compression stroke. Mounted in the pipe 35 is a closing member having the form of a slide valve 60 formed with a port 61. This slide is connected to the short arm of a rocker 62, the long arm of which is engaged by a pin 63 on the rack 15, so that the reciprocatory movement of the pistons is transmitted to the slide 60. The arrangement is such that the port 61 connects the compression chamber 3 to the cylinder 33 only if suction pressure acts on the opening 59, the connection being severed when the compressor piston 5, during its compression stroke, moves to the other side of the opening 59 and exposes same to the pressure at the rear of the compressor piston 5. In this manner interference of this pressure with the operation of the fuel-regulating device 5 30—34 is prevented.

Fig. 3 is a diagram illustrating the way in which the compressor is controlled by an increase of the delivery pressure. A B C D A is the diagram for the normal operation of the compressor. Compression occurs from the suction pressure p_1 to the delivery pressure p_2 . If the delivery pressure is raised to p_{21} , the new compressor diagram is A B₂ C₂ D₁ A. The suction line D₁ A of this new diagram is shorter than the suction line D A of the normal diagram. The quantities of gas drawn in, and consequently also the quantities of gas delivered, vary in the same proportion as these lines.

Fig. 4 is a diagram showing the control by a reduction of the suction pressure. Here again A B C D A is the diagram of normal operation. If the suction pressure is reduced from p_1 to p_{11} , the new diagram is A₂ B₁ C D₂ A₂. The performances are proportioned similarly as the line B C (at normal performance) relative to the line B₁ C (at reduced suction pressure).

Fig. 5 is the diagram of a compressor in which the performance is regulated by simultaneously varying the delivery and suction pressures in opposite senses. If the performance of the compressor (the normal diagram of which is again A B C D A), shall be reduced, the suction pressure is reduced from p_1 to p_{11} , while the delivery pressure is increased from p_2 to p_{21} . The new diagram is A₂ B₂ C₂ D₂ A₂. The performance is

reduced in the proportion of the products from suction line and suction pressure.

Fig. 6 shows a free piston motor compressor with a pneumatic buffer comprising a cylinder 65 and a piston 66 which absorbs energy during the power stroke of the freely moving masses, stores this energy in its dead space under the form of compressed gas, and returns it to the freely moving masses during their return stroke. The amount of energy absorbed and delivered by the buffer is regulated, according to this invention, by varying the pressure existing in the buffer space at the beginning of compression. To this end the space 67 is connected to the storage tank 13 by a pipe 69 which opens into the buffer space 15 at 68, i. e. in the vicinity of the position which the end of the buffer piston occupies at the beginning of the power stroke.

The operation of this device appears from Fig. 7 which shows the diagram of such a buffer. If the pressure in the tank 13 has its normal value p_m , compression in the buffer occurs from this pressure p_m along line S T. If the pressure in the tank 13 rises to the higher value p_n , the new compression line is U V, and the energy absorbed and delivered by the buffer is raised by an amount corresponding to the area S T V U S.

The buffer, or an additional compressor or the like, may also be so arranged that it absorbs energy upon the return stroke of the freely moving mass, and delivers such energy upon the power stroke of the same. If the compressor piston is larger than the motor piston, the differential piston area of the two, and the space 70 (Fig. 1) in which this differential area operates, may constitute the buffer or additional compressor. The amount of energy absorbed by such buffers or compressor chambers during the return stroke of the freely movable masses may also be varied by pressure variation, as illustrated, for instance, in Fig. 8. The space 70 adjoining the left hand side of the compressor piston 5 may, for example, be a scavenging pump equipped with suction valves 71 and delivery valves 72. A pipe 73 extends from the delivery valves 72 to the scavenging air tank 74 (Fig. 6). A throttle 75 is inserted in this pipe which, in a manner similar to the throttle according to Fig. 2, is influenced by the pressure in the tank 13 in such manner that its throttling action is increased when the pressure rises, and vice versa.

I wish it to be understood that I do not desire to be limited to the exact details of construction shown and described for obvious modifications will occur to a person skilled in the art.

I claim:—

1. A free piston motor compressor comprising in combination, a motor cylinder and at least one compressor cylinder arranged on either side thereof, a free piston in each cylinder, comprising a motor piston and a compressor piston arranged on the same side of the motor cylinder being directly connected with each other, means for varying one of the initial and end pressures in said compressor cylinders and means for at the same time varying the supply of fuel to said motor cylinder in such manner that the length of the piston stroke remains substantially constant.

2. A free piston motor compressor comprising in combination, a motor cylinder and at least one compressor cylinder arranged on either side thereof, a free piston in each cylinder, comprising a motor piston and a compressor piston arranged on the same side of the motor cylinder being directly connected with each other, means for vary-

- ing both the initial and end pressures in said compressor cylinders and means for at the same time varying the supply of fuel to said motor cylinder in such manner that the length of the piston stroke remains substantially constant.
3. A free piston motor compressor comprising in combination, a motor cylinder, at least one compressor cylinder arranged on either side thereof and at least one additional compression cylinder, a free piston in each of said cylinders, comprising a motor piston and a compressor piston arranged on the same side of the motor cylinder being directly connected with each other, means for varying one of the initial and end pressures in said compressor and additional compression cylinders, and means for at the same time varying the supply of fuel to said motor cylinder in such manner that the length of the piston stroke remains substantially constant.
- 20 4. A free piston motor compressor comprising in combination, a motor cylinder, at least one compressor cylinder arranged on either side thereof and at least one additional compression cylinder, a free piston in each of said cylinders, comprising a motor piston and a compressor piston arranged on the same side of the motor cylinder being directly connected with each other, means for varying both the initial and end pressures in said compressor and additional compression cylinders, and means for at the same time varying the supply of fuel to said motor cylinder in such manner that the length of the piston stroke remains substantially constant.
- 25 5. A free piston motor compressor comprising in combination, a motor cylinder, a plurality of compressor cylinders arranged on either side thereof, a free piston in each of said cylinders, comprising a motor piston and a compressor piston arranged on the same side of the motor cylinder being directly connected with each other, means for varying one of the initial and end pressures in part of said compressor cylinders and means for at the same time varying the supply of fuel to said motor cylinder in such manner that the length of the piston stroke remains substantially constant.
- 30 6. A free piston motor compressor comprising in combination, a motor cylinder, a plurality of compressor cylinders arranged on either side thereof, a free piston in each of said cylinders, comprising a motor piston and a compressor piston arranged on the same side of the motor cylinder being directly connected with each other, means for varying both the initial and end pressures in part of said compressor cylinders and means for at the same time varying the supply of fuel to said motor cylinder in such manner that the length of the piston stroke remains substantially constant.
- 35 7. A free piston motor compressor comprising in combination, a motor cylinder, at least one compressor cylinder arranged on either side thereof, and at least one pneumatic buffer cylinder, a free piston in each cylinder, comprising a motor piston and a compressor piston arranged on the same side of the motor cylinder being directly connected with each other, means for varying one of the initial and end pressures in said compressor cylinders and in said pneumatic buffer cylinder, and means for at the same time varying the supply of fuel to said motor cylinder in such manner that the length of the piston stroke remains substantially constant.
- 40 8. A free piston motor compressor comprising in combination, a motor cylinder, at least one compressor cylinder arranged on either side thereof, a free piston in each cylinder, comprising a motor piston and a compressor piston arranged on the same side of the motor cylinder being directly connected with each other, means for varying one of the initial and end pressures in said compressor cylinders and in said pneumatic buffer cylinder, and means for at the same time varying the supply of fuel to said motor cylinder in such manner that the length of the piston stroke remains substantially constant.
- 45 9. The combination, with the free piston motor compressor of claim 2, of means for keeping the relation between the initial and the end pressures in said compressor cylinders constant.
10. The combination, with the free piston motor compressor of claim 4, of means for keeping the relation between the initial and the end pressures in said compressor cylinders constant.
11. The combination, with the free piston motor compressor of claim 1, of means for regulating the fuel supply to the motor cylinder in dependency from one of the initial and end pressures, subjected to variation, in the compressor cylinders.
12. A free piston motor compressor comprising in combination, a motor cylinder and at least one compressor cylinder arranged on either side thereof, a free piston in each cylinder, comprising a motor piston and a compressor piston arranged on the same side of the motor cylinder being directly connected with each other, means for varying one of the initial and end pressures in said compressor cylinders, means for at the same time varying the supply of fuel to said motor cylinder in such manner that the length of the piston stroke remains substantially constant, and a single adjusting member adapted to effect the variation of one of said pressures and of said fuel supply.
13. A free piston motor compressor comprising in combination, a motor cylinder and at least one compressor cylinder arranged on either side thereof, a free piston in each cylinder, comprising a motor piston and a compressor piston arranged on the same side of the motor cylinder being directly connected with each other, means for varying both the initial and end pressures in said compressor cylinders, means for at the same time varying the supply of fuel to said motor cylinder in such manner that the length of the piston stroke remains substantially constant, and a single adjusting member adapted to effect the variation both of said pressures and of said fuel supply.
14. A free piston motor compressor comprising in combination, a motor cylinder and at least one compressor cylinder arranged on either side thereof, a free piston in each cylinder, comprising a motor piston and a compressor piston arranged on the same side of the motor cylinder being directly connected with each other, means for varying one of the initial and end pressures in said compressor cylinders, means for at the same time varying the supply of fuel to said motor cylinder in such manner that the length of the piston stroke remains substantially constant, and a single source of power adapted to move both said members.
15. A free piston motor compressor comprising in combination, a motor cylinder and at least one compressor cylinder arranged on either side thereof, a free piston in each cylinder, comprising a motor piston and a compressor piston arranged on the same side of the motor cylinder being directly connected with each other, means for varying one of the initial and end pressures in said compressor cylinders, means for at the same time varying the supply of fuel to said motor cylinder in such manner that the length of the piston stroke remains substantially constant, and a single source of power adapted to move both said members.

- 5 ranged on the same side of the motor cylinder being directly connected with each other, means for varying both the initial and end pressures in said compressor cylinders, means for at the same time varying the supply of fuel to said motor cylinder in such manner that the length of the piston stroke remains substantially constant, and a single source of power adapted to move both said members.
- 10 16. A free piston motor compressor comprising in combination, a motor cylinder and at least one compressor cylinder arranged on either side thereof, a free piston in each cylinder, comprising a motor piston and a compressor piston arranged 15 on the same side of the motor cylinder being directly connected with each other, a compressed air conduit connected to said compressor cylinders, a valve inserted in said conduit and subjected to the discharge pressure of said compressor, a spring arranged to counteract the discharge pressure acting on said valve, means for varying the tension of said spring in dependency from the pressure prevailing in said conduit to the rear of said valve and means for varying the supply of 20 fuel to said motor cylinder in such manner that the length of the piston stroke remains substantially constant.
- 15 17. A free piston motor compressor comprising in combination, a motor cylinder and at least one compressor cylinder arranged on either side thereof, a free piston in each cylinder, comprising a motor piston and a compressor piston arranged 25 on the same side of the motor cylinder being directly connected with each other, suction valves 30 on said compressor cylinders, a suction conduit communicating with said valves, a pressure conduit for the gas compressed in said compressor cylinders, means for varying the cross-sectional area of passage of said suction conduit in dependency from the pressure in said pressure conduit and means for varying the supply of fuel to 35 said motor cylinder in such manner that the length of the piston stroke remains substantially constant.
- 20 18. A free piston motor compressor comprising 40
- in combination, a motor cylinder, at least one compressor cylinder arranged on either side thereof, and at least one pneumatic buffer cylinder, a free piston in each of said cylinders, comprising a motor piston and a compressor piston arranged 45 on the same side of the motor cylinder being directly connected with each other, each buffer cylinder being fixed in alignment with the corresponding compressor cylinder, a pressure conduit for the gas compressed in one compressor cylinder, said pressure conduit being connected to the corresponding buffer cylinder near the point at which the end face of said buffer piston is located before compression is started, and means for varying the fuel supply to said motor cylinder in such manner that the length of the piston stroke remains substantially constant.
- 25 19. A free piston motor compressor comprising in combination, a motor cylinder, at least one compressor cylinder arranged on either side 20 thereof and an additional compression cylinder, a free piston in each of said cylinders, comprising a motor piston and a compressor piston arranged 25 on the same side of the motor cylinder being directly connected with each other, means for 30 varying one of the initial and end pressures in said compressor cylinders, and means for at the same time varying the supply of fuel to said motor cylinder in such manner that the length of the piston stroke remains substantially constant. 35
- 30 20. A free piston motor compressor comprising in combination, a motor cylinder, at least one compressor cylinder arranged on either side thereof and an additional compression cylinder, a free piston in each of said cylinders, comprising 35 a motor piston and a compressor piston arranged on the same side of the motor cylinder being directly connected with each other, means for 40 varying both the initial and end pressures in said compressor cylinders, and means for at the same time varying the supply of fuel to said motor cylinder in such manner that the length of the piston stroke remains substantially constant.

HERMANN JÄNICKE. 45
